UNITED STATES PATENT OFFICE.

WILLIAM E. ELLIOTT, OF GRAND RAPIDS, MICHIGAN, ASSIGNOR TO AMERICAN
BUTTON & FASTENER CO., OF AUGUSTA, MAINE, A CORPORATION OF MAINE.

ATTACHING MACHINE.

1,410,559.

Specification of Letters Patent. Patented Mar. 28, 1922.

Application filed May 9, 1919. Serial No. 295,825.

To all whom it may concern:

Be it known that I, WILLIAM E. ELLIOTT, a citizen of the United States, residing at Grand Rapids, in the county of Kent and State of Michigan, have invented certain Improvements in Attaching Machines, of which the following description, in connection with the accompanying drawings, is a specification; like reference characters on the drawings indicating like parts in the several figures.

My invention relates to attaching machines and especially to those for affixing fasteners to various kinds of work by means of securing devices. As an example of machines of this character may be noted those employed for attaching buttons to shoes and the like by means of staples.

Such existing machines as above mentioned, so far as I am aware, take the buttons from hoppers for delivery to the attaching mechanism, the staples being similarly fed from separate receptacles or formed one by one as the buttons are delivered; or they handle the buttons and staples assembled in pairs from magazine tubes in which they are carried loosely in series. These feeding, staple-making and magazine arrangements increase the complication of the attaching apparatus and interfere with the certainty of its action. An object of this invention is to provide a machine organized for operating upon buttons or like objects and their securing devices or staples fixed in a definite relation upon a holder to form a package. In the accomplishment of this object, as shown, I employ means co-operating with the objects, their securing devices and the holder therefor, to free the objects and securing devices successively for delivery to mechanism for operating upon them.

Such a machine may be relatively simple in construction and will operate accurately. The holder is preferably in the form of a strip, the freeing means acting upon it to cause its advance and the successive delivery of the fasteners and securing devices.

Another object of the invention is to cause the release of the fasteners and the operation upon them to occur in correct timed relation. To this end, there is included means for changing the extent of advance of the holder-strip so that a fastener is delivered for each attaching operation.

A further object of the invention is to

simplify and render more positive the fastener-inserting operation. For this purpose a single member is employed both to successively feed fasteners by engagement with the associated securing devices from a suitably supported series and attach to the work the fastener previously fed. I prefer to utilize for this purpose a reciprocatory member engaging the securing devices of adjacent fasteners to move them toward the work, one fastener being fed by this movement while another is being attached. To permit the member to enter between the fasteners, it may also be mounted to oscillate.

An additional object of the invention concerns the provision of novel and effective means for actuating the fastener-attaching means and work-retaining means toward and from a work-support. There is herein disclosed an actuating member for each of said means, one being directly driven and the other operating by a connection to its companion. To allow this to be carried out without interference with the movement of the parts, there is shown a yieldable connection between one of the means and its actuating member. To provide for the correct timing of the operations there is lost motion in the connection between the actuating members. The travel of the retaining member from the support is preferably effected by a spring, this ensuring prompt separation of the retaining member from the work.

Upon consideration of the following description and claims, other objects will become evident, reference being had to the annexed drawings, in which—

Fig. 1 is a side elevation of one embodiment of my improved attaching machine, parts being in section;

Fig. 2 is an enlarged transverse section on the line 2—2 of Fig. 9;

Fig. 3 is a top plan view of the mechanism for separating the fasteners from the mounting strip;

Fig. 4 is a side elevation of said mechanism, looking from the right in Fig. 3;

Fig. 5 is a vertical section on the line 5—5 of Fig. 3;

Fig. 6 is an enlarged vertical section of the separating mechanism, particularly illustrating its action upon the fasteners and their mount;

Fig. 7 is a perspective view of the pres-

105

110

sure-rolls of the separating mechanism and their support;

Figs. 8, 9, 10 and 11 are longitudinal, vertical, sectional details of the fastener-feeding and attaching mechanism, illustrating successive positions of the elements;

Fig. 12 is a top plan view of the fastener-engaging portion of the feeding and driving member;

10 Fig. 13 is an enlarged perspective view of the same portion of said member;

Fig. 14 is a top plan view of the lower end of the raceway; and

15 Figs. 15 and 16 are enlarged details in side elevation and top plan, respectively, of the mounting member or holder with the fasteners in place thereon.

My invention is herein described, as one of its many applications and embodiments, 20 in connection with a machine for attaching buttons to shoes or other work by means of staples. The buttons are usually looked upon as fastening devices for the work and the staples as devices for securing buttons 25 to the work, though the button and staple together may be considered as also comprehended by the term "fastener". Upon a base 10 is supported a frame-member 12, near one end of which is fixed a work-support 30 or anvil 14, which may be inclined to the horizontal to facilitate the application of the work to it. The frame-member has separated sides 16, 16, upon inclined upper faces of which, in opposite ways 18, 18, is carried 35 for reciprocatory movement a fastener-supporting member furnished by a raceway 20, this raceway being retained in the supporting ways by removable plates 21, 21 fixed upon the top of each of the walls 16. Since 40 the raceway is designed to convey buttons having eyes with staples inserted therein, it is provided with a longitudinal eye-receiving groove 22 (Fig. 2) and lateral staple-receiving grooves 24, 24, which extend horizontally 45 at each side of the groove 22, the grooves 24 being beneath separated cover-plates 26, 26, which retain the staples and buttons in place in their movement down the raceway, and, by their separation at 28, furnish a passage 50 through which the button-eyes travel. In the cover-plates, at each side of the space 28, is a longitudinal depression 30 curved laterally to conform to the under side of the head of the button which is to be supported 55 and conveyed by it.

Rotatably mounted upon arms 32, 32 at the rear of the base 10 is a spool or reel 34 for the fastener package, this package preferably consisting of a holder-strip furnished 60 by a ribbon 36 of paper or other suitable material. As best illustrated in Figs. 1, 15 and 16, this strip has a series of equally spaced, short longitudinal slits 38 to receive the eyes *b* of the buttons *B*, and the adjacent 65 transverse corrugations 40 through which

the legs of staples *S* are forced, the yokes of these staples passing through the respective button eyes. The end of the strip 36, with the points of the staples extending in the direction of advance, is carried between 70 guide-projections 42, 42 from a member 44 and then over plates 46, 46 located upon raised side walls of the member 44. The adjacent edges of the plates are spaced from one another at 48 to allow the eyes of the buttons to pass between them, and at each side of this space, upon the corresponding plate, is a vertical flange 50, the upper edge of which furnishes a support for the heads of the buttons. The member 44 is carried 75 upon a bracket 52 projecting from one side of the upper extremity of the raceway, it being fixed to the latter by a clamping portion 54 of the bracket, through the sides of which are threaded opposite screws 56, 56, 80 which serve to fix the clamping portion in place upon the raceway, and also enable it to be adjusted laterally to bring the fastener-receiving slots and depressions of the raceway and the space 48 and flanges 50 into 85 alignment. Upon the member 44, beneath the forward ends of the plates 46, 46, is journaled transversely of the machine a centrally divided feed-roll 58 having upon its periphery engaging-ribs or projections, which, by 90 their contact with the holder-strip 36, insure its advance when the roll is rotated. Fastened to the roll sections against the outer face of each of the side plates of the member 44 is a pinion 60, with which mesh 100 idler pinions 62 fixed to a spindle 66 rotatable in the member 44. One of the pinions 62 is engaged by a pinion 64 turning about a stud on the right-hand side-plate (Fig. 3). Rotatable about a stud on the left-hand 105 side-plate is a sleeve having fast upon it a pinion 67 engaging the adjacent idler 62 and also having a head or finger-piece 68, by which the roll 58 may be rotated manually 110 to cause the feed of the member 36 when it is started in its course through the machine. The pinion 64 has meshing with it a gear 70 rotatable about a spindle 72 journaled in the member 44. Adjacent to the gear 70 is carried, to turn about the spindle, a ratchet 115 wheel 74, and outside this the spindle has fixed upon it an arm 76. Pivoted upon the arm is a ratchet 78 held by a spring 80 in contact with the teeth of the ratchet wheel 74. Fastened upon the spindle 72 is an arm 120 82, to which is articulated a link 84 having at its opposite or lower extremity a pin 86, which pivotally connects it to a bell-crank 125 lever 88 fulcrumed at 90 between the side-plates 16. From one angle of the bell-crank 88, which is shown as in the form of a triangular plate, a link 92 connects it to a rock-lever 94 fulcrumed upon lugs 96 depending from the base 10. To the opposite end of the lever 94 is joined an eccentric rod 98, 130

which receives movement from an eccentric 100 fast upon a shaft 102 journaled upon the base. This shaft also carries a pulley 104, to which power may be applied from any 5 convenient source. The pulley and shaft are preferably joined by a one-revolution clutch, which is not illustrated. Situated opposite the feed-roll 58 are lower and upper pressure-rolls 106 and 108, 108, spaced 10 from one another to contact with the feed-roll along horizontal lines separated by a considerable angle peripherally of said feed-roll. The pressure-rolls preferably have peripheral projections corresponding to those 15 upon the feed-roll and increasing the effectiveness of their engagement with the holder-strip 36. The lower pressure-roll 106 is shown as journaled at its opposite extremities in supporting plates 110, 110 pivoted to oscillate upon a frame 112 pivotally secured at 114 upon the bracket 52. There are two of the upper rolls 108 separately mounted for rotation upon the plates 110, they being spaced from one another to allow 20 the entrance between them of the end of the raceway. A coil spring 118, surrounding the pivot 114 and contacting with pins 120 fixed in the frame and bracket, causes the pressure-rolls to be forced against the strip 36 as it passes about the feed-roll. 25

When the end of the holder-strip is introduced into the separating mechanism, its edges are supported by opposite curved walls 122, 122 upon the member 44, while 35 the under sides of the button heads at the forward extremity of the strip are supported by the plates 46 and their flanges 50. The staples pass with the strip beneath the plates 46. As is most clearly shown in Fig. 6 of 40 the drawings, the end of the strip is carried about the feed-roll, between it and the pressure-rolls. Power being applied to the machine to oscillate the rock-lever 42 and through the connections the ratchet arm 76, 45 the ratchet mechanism and interposed gearing rotates the feed-roll in the direction of the arrow in Fig. 6. This advances the strip, the buttons being successively caught by the rear edges of the plates 46 and riding upon 50 the tops of the flanges 50. In this movement the strip and staples are raised toward the under side of the plates 46, and when they reach the forward ends, the points of the staples are alined with the grooves 24 in 55 the raceway, which they enter. The change in the direction of advance of the strip, as it travels downward between the feed-roll and pressure-rolls, separates it from both the button and staple, the former held 60 against movement in this direction by the plates and the latter by the raceway and button-eye. The fasteners are thus successively stripped from the holder and delivered to the raceway, down which they are 65 left free to slide. To control the effective stroke of the ratchet mechanism, there is shown surrounding a portion of the periphery of the ratchet wheel 74, a segmental shield 124 mounted to turn about the spindle 72 and having an arm 126 carrying at 70 its outer extremity a horizontal pin 128. This pin co-operates with a spring dog 130 fixed to the arm, which dog may engage any one of a series of openings 132 arranged along an arc upon a plate 134 secured at one 75 side of the member 44. By pressure upon the pin 128, the dog may be released from the openings and the shield 124 moved to any desired position about the ratchet wheel and secured in place by the engagement of 80 the dog with another opening. The ratchet 78 may thus, at a predetermined point in its stroke, be raised from the ratchet wheel by engagement with the shield, and in this manner the time and extent of contact of 85 the ratchet mechanism be controlled. In this way, for each stroke of the lever 94 which produces an attaching operation, as will be hereinafter described, the separating mechanism may be adjusted to advance 90 the holder-strip to release another button and staple and deliver it to the raceway.

As the buttons and associated staples slide down the raceway, they come under the control of the first of a series of stop-devices. 95 In the wall of the raceway is shown a horizontal bore or recess 136, at the inner extremity of which is a contracted opening which retains, projecting through it into the raceway, a ball 138 pressed in this direction by a helical spring 140 between it and the opposite end of the recess, these parts being beneath a plate 142 secured upon the top of the raceway beyond the cover-plates 26. This device arrests the movement of 100 105 the forward staple and its associated button in the series in the raceway at what may be termed a feed position, from which the fasteners are taken for presentation to the final or attaching position. Beyond the 110 stop-device 138 is a similar device 144 situated at the opposite side of the raceway beneath a plate 146. With the projecting ball of this device contacts the staple as it is advanced under the influence of a feeding 115 and driving member to be hereinafter described, and, after the staple and associated button have passed, retains them against upward displacement under the influence of vibratory movement of the raceway in contact with a stop-device 148 of the same character and located beneath the plate 142. This last-named device holds the fastener at the end of the raceway in position for delivery to the attaching mechanism. Still 120 125 lower, on the same side of the raceway with the stop 144, is a like device 149 which acts, by its friction against the staple, to prevent said staple with its button from falling away from the driver.

Mounted to oscillate about the pin 86 is an operating member or lever 150, which acts upon the fasteners to both feed, advancing them from the stop-device 138 to the device 148, and drive or insert them in the work carried upon the anvil 14. The lever 150 has an upper feeding projection 152, at the lower side of which is a contact face 154 for engagement with the outer ends of the staple yokes. Through the projection is a slot 156 permitting the button eyes to pass. At the lower extremity of the lever 150 is a driving projection 158, this having separated notches 160 for engagement with the staple yokes and adjacent inclined walls 162 which contact with the correspondingly inclined portions of the yokes, as is illustrated in Fig. 12 of the drawings. A slot 164 in the projection 158 provides for the passage of the button eyes. The upper end of the lever 150 has an extension 166 which is connected by a spring 168 to a pin 170 projecting rearwardly from the edge of the bell-crank lever 88. A pin 172 is carried in a horizontal position upon a depending portion 174 of the operating lever 150, this moving over the edge of a cam-plate 176 secured to the inner portion of one of the side walls 16 of the frame. When the pin 172 is in contact with a raised portion 178 of the cam-plate, as appears in Figs. 1 and 8 of the drawings, the feeding and driving projections 152 and 158 are held below the raceway out of engagement with the fasteners therein. As the lever moves downwardly under the influence of the driving mechanism, the pin rides down an incline 180 of the cam-plate, and when it reaches a surface 182 thereon, the projections have entered between the staples (Fig. 9), 158 co-operating with the staple held by the stop-device 148, into contact with which it has been brought by a previous operation, and the projection 152 with the staple retained by the stop-device 138. Upon the movement of the operating lever in the direction just described, the pin 172 rides over and depresses a rock-lever 184 fulcrumed adjacent to one face of the cam-plate. This rock-lever is held in its normal position yieldably to move in either direction about its fulcrum point by a tension lever 186, separated projections 188, 188 of which contact with the rock-lever 184 at opposite sides of its fulcrum, the levers being drawn into contact by a spring 190 extending between the lever 186 and the frame. In the travel of the lever 150 in the opposite direction, or upwardly, the pin 172 engages a depression 192 in an end of the rock-lever 184. As the rock-lever turns about its fulcrum under the pressure of the operating lever, it raises the latter out of contact with the cam-plate (Fig. 11), thus carrying the projections 152 and 158 below the plane of the staples and out of contact with them so

they shall not be displaced upwardly in the raceway.

Mounted to turn about the fulcrum 90 of the actuating lever 88 for the feeder and driver 150 is a second actuating lever 194 having at its upper end an enlargement, in which is a segmental slot 196 which the pin 86 of the lever 88 enters. A spring 198 surrounding the fulcrum 90 with its ends bearing against pins 200 fixed in the lever 194 and in the frame holds the lever against a portion of the frame, with its upper extremity against a cross-bar 202 of the raceway and thus normally maintains said raceway in its raised position separated from the anvil 14. Upon the opposite side of the lever 194 from the cross-bar is a collar 204 secured to a rod 206 guided in a bore 208 in the under side of the raceway. Normally, or when the machine is at rest, there is a space 205 between the collar 204 and the lever 194. A spring 210 coiled about the rod abuts at its lower extremity against the bar 202 and at its upper end against a collar 212 fixed to the rod and also serving to limit the movement of the latter upwardly by contact with the raceway.

Fig. 8 of the drawings shows the operating mechanism in its initial position. The work to which the fasteners are to be attached having been placed upon the anvil 14, as the actuating lever 88 is turned in a clockwise direction by the driving mechanism, the operating lever 150 is first brought by a movement of its pin 172 over the cam-incline 180 until its projections 152 and 158 engage the staples of fasteners held by the stop-devices 138 and 148, as is illustrated in Figs. 9 and 12. At this time, the pin 86 moves through the slot 196, providing for lost-motion between the actuating levers 88 and 194, and no oscillation of the actuating lever 194 is produced. When, however, the projections 152 and 158 begin to draw the respective fasteners at the feeding and delivering positions from the stop devices the first for advance to the delivery position and the second for insertion in the work, the pin 86 reaches the end of the slot and contacting therewith swings the lever 194 also in a clockwise direction. This, by its contact with the collar 204, communicates movement to the raceway, the tension of the spring 210 being sufficient to resist compression. In this way, the lower end of the raceway is brought into contact with the work positioned upon the anvil to fix or retain it for the attaching operation. Upon this contact, the spring 210 yields, permitting the advance of the levers 194 and 88 together, to maintain the work under the pressure of the raceway and continue the movement of the driving lever 150 for the staple inserting operation. This is shown in Fig. 10 of the drawings. The rock-lever 184

94, under the influence of the driving eccentric, now travels in the opposite direction, reversing the movement of the bell-crank lever 88 and causing the upward travel of the lever 150. As this retreats, the end of the raceway remains for a very short time in contact with the work under the tensions of the spring 210; but immediately the pin 86, in the anti-clockwise movement 5 of the lever 88, leaves the end of the slot 196 in lever 194, the spring 198 moves the lever against the bar 202 to raise the raceway and release the work, thus permitting it to be shifted by the operator for the attachment 10 of another button. It will therefore be evident that it is unnecessary to await the contact of the pin with the opposite end of the slot before the work is freed. This gain 15 in time substantially increases the rate at 20 which the machine may be operated. When the lever 194 reaches the upward extreme of its travel, the momentum of the raceway causes it to slide in the guideway 18 through the extent of the space 205 or until the collar 25 204 strikes the lever. This produces a sharp concussion which effectively advances the buttons and staples along the raceway, overcoming any tendency to clog therein. Following this, the raceway falls by gravity 30 until checked by the contact of the bar 202 with the lever 194, giving a second fastener-clearing and feeding shock. When the pin 172 in its rearward travel over the surface 182 engages the depression 192 of the lever 35 184, the latter, tilting, lowers the lever 150 to carry it clear of the series of staples (Fig. 11). After a time the pin 172 slips out of the depression and comes to rest upon the cam-projection 178 ready for another operation. As has been already pointed out, the 40 delivery of the fasteners, or their stripping from the mount by the separating mechanism, is timed to synchronize with the attaching operation so that the proper series 45 of fasteners is maintained in the raceway, it never being permitted to become emptied or over-supplied.

Having described my invention, what I claim as new and desire to secure by Letters 50 Patent of the United States is:

1. In a machine for operating upon objects and securing devices therefor fixed upon a holder in definite relation to form a package, operating mechanism, and means 55 co-operating with the objects and securing devices and with the holder, said means being arranged to free the objects and their securing devices successively from the holder for delivery to the operating mechanism.

2. In a machine of the class described, a holder arranged to maintain fasteners and securing devices for said fasteners, in a pre-determined relation operating means, and 65 means for separating the fasteners and se-

curing devices and the holder for the delivery of said fasteners and securing devices to the operating means.

3. In a machine of the class described, a holder upon which fasteners and securing devices therefor are fixed, means for attaching the securing devices to the work, and means for drawing apart the holder and the fasteners and securing devices for the attachment of the latter. 75

4. In a button-attaching machine, a strip carrying in a series buttons and associated staples, means for inserting the staples in the work to secure the buttons thereto, and means for successively freeing the buttons 80 and their staples from the strip for delivery to the inserting means.

5. In a machine of the class described, a holder for fasteners and securing devices for said fasteners, attaching means, conveying 85 means leading to the attaching means, and means advancing the holder and separating the fasteners and securing devices and the holder and delivering said fasteners and securing devices to the conveying means. 90

6. In a button-attaching machine, a strip carrying in a series buttons and associated staples, means for inserting the staples in the work to secure the buttons thereto, a raceway delivering to the inserting means, 95 and means for successively freeing the buttons and their staples from the strip and presenting them to the raceway.

7. In a machine of the class described, a holder for fasteners and securing devices for 100 said fasteners, attaching means, conveying means leading to the attaching means, and means for drawing the holder from the fasteners and securing devices and delivering said fasteners and securing devices to the 105 conveying means.

8. In a machine of the class described, a holder for fasteners and securing devices assembled therewith, mechanism for operating upon the fasteners and securing devices, and means acting upon the holder to separate it from the fasteners and securing devices and permit them to be delivered to the 110 operating mechanism.

9. In an attaching machine, a strip carrying fasteners and securing devices assembled therewith, mechanism for attaching the securing devices to the work, and means for advancing the strip and changing the direction of advance to separate said strip from the fasteners and securing devices for the delivery of the latter to the attaching mechanism. 115

10. In an attaching machine, a strip carrying fasteners and securing devices assembled therewith, mechanism for attaching the securing devices to the work, movable means for engaging the strip, and relatively fixed means for engaging the fasteners and their securing devices whereby the latter are separated. 120 125 130

- 6
- rated from the strip for delivery to the attaching mechanism.
11. In an attaching machine, a strip carrying fasteners and securing devices assembled therewith, mechanism for attaching the securing devices to the work, separated supports for the fasteners and securing devices, one of which supports delivers to the attaching mechanism, and means for advancing the strip between the supports while the fasteners and securing devices pass from one support to another.
12. In a button-attaching machine, a strip carrying in a series buttons and associated staples, mechanism for inserting the staples in the work to secure the buttons thereto, a button and staple support, a raceway separated from the support and delivering to the inserting mechanism, and means for advancing the strip through the space between the support and raceway while the staples enter the raceway and carry the buttons thereto.
13. In an attaching machine, a strip carrying fasteners arranged in a series, mechanism for attaching the fasteners to the work, means for advancing the strip step by step and separating it from the fasteners for the successive delivery of said fasteners to the attaching mechanism, and means arranged to change the extent of advance of the strip.
14. In an attaching machine, a strip carrying fasteners arranged in a series, mechanism for attaching the fasteners to the work, means for advancing the strip step by step and separating it from the fasteners for the successive delivery of said fasteners to the attaching mechanism, ratchet mechanism for actuating the advancing means, and means arranged to change the effective throw of the ratchet mechanism.
15. In an attaching machine, a strip carrying fasteners arranged in a series, mechanism for attaching the fasteners to the work, means for advancing the strip step by step and separating it from the fasteners for the successive delivery of said fasteners to the attaching mechanism, a ratchet and ratchet wheel for actuating the advancing means, and means for varying the time of engagement of the ratchet and ratchet wheel.
16. In an attaching machine, a strip carrying fasteners arranged in a series, a feed-roll acting to advance the strip and separate it from the fasteners, and pressure-rolls cooperating with the feed-roll and between which the fasteners pass on their way to the attaching mechanism.
17. In an attaching machine, a strip carrying fasteners arranged in a series, a feed-roll acting to advance the strip and separate it from the fasteners, oscillatory supporting members situated adjacent to the feed-roll, and a pressure-member carried in each of the supporting members for co-operation with the feed-roll and being spaced from one another.
18. In an attaching machine, a strip carrying fasteners arranged in a series, a feed-roll acting to advance the strip and separate it from the fasteners, oscillatory supporting members situated adjacent to the feed-roll, a pressure-roll journaled upon both supports, and pressure-rolls journaled in alignment with each other upon the supports, said pressure-rolls co-operating with the feed-roll.
19. In a machine for attaching fasteners by securing devices, means for supporting a series of fasteners, with associated securing devices, and a member arranged to engage the securing devices to successively feed them with the fasteners from the supporting means and to attach to the work those previously fed.
20. In a machine for attaching fasteners by securing devices, a support for a series of fasteners with associated securing devices, said support including means for holding a fastener in position for application to the work and means for holding the preceding fastener ready to be fed to the applying position, said holding means engaging the securing devices associated with the respective fasteners, a work-support, and means acting simultaneously to advance the fasteners and their securing devices from the applying position toward the work-support and from the feeding position toward the applying position.
21. In a machine for attaching fasteners by securing devices, a support for a series of fasteners with associated securing devices, said support including means for holding a fastener in position for application to the work and means for holding the preceding fastener ready to be fed to the applying position, said holding means engaging the securing devices associated with the respective fasteners, a work-support, and a unitary member arranged to engage securing devices to advance them and the corresponding fasteners from the applying position toward the work-support and from the feeding position toward the applying position.
22. In a machine for attaching fasteners by securing devices, a support for a series of fasteners with associated securing devices, said support including means for holding a securing device and its fastener in position for application to the work and means for holding the preceding securing device and fastener ready to be fed to the applying position, a work-support, and a reciprocatory member arranged to engage the securing devices associated with adjacent fasteners and move them toward the work-support.
23. In a machine for attaching fasteners by securing devices, a support for a series

of fasteners with associated securing devices, said support including means for holding a securing device and its fastener in position for application to the work and means 5 for holding the preceding securing device and fastener ready to be fed to the applying position, a work-support, and a reciprocatory and oscillatory member arranged to engage the securing devices associated with 10 adjacent fasteners and move them toward the work-support.

24. In a machine for attaching fasteners by securing devices, means for supporting a series of fasteners with associated securing 15 devices, and a member having an attaching portion and a feeding portion contacting with the securing devices.

25. In a machine for attaching fasteners, a support for a series of fasteners, said support 20 including means for holding a fastener in position for application to the work and means for holding the preceding fastener ready to be fed to the applying position, a work-support, and a movable attaching member having projections to enter between 25 fasteners in the applying and feeding positions and between the fastener in feeding position and the next preceding fastener.

26. In a button-attaching machine, means 30 arranged to hold buttons and associated staples, and a staple-inserting member co-operating with the holding means and having a button and staple-feeding portion and an independent inserting portion.

35. 27. In a button-attaching machine, a raceway arranged to hold buttons and associated staples, an anvil at one extremity of the raceway, and a driver co-operating with the raceway and anvil and having a 40 staple-inserting projection and a staple-feeding projection.

28. In a button-attaching machine, a raceway arranged to hold buttons and associated staples, an anvil at one extremity of the raceway, and a driver co-operating with the raceway and anvil and having a staple-inserting projection and a staple-feeding projection, the projections having spaces 45 through which portions of the buttons may 50 pass.

29. In a button-attaching machine, a raceway arranged to hold buttons and associated staples, an anvil at one extremity of the raceway, a driver having feeding and 55 staple-setting portions, means for reciprocating the driver toward and from the anvil to effect the setting of the forward staple, and means for oscillating said driver to enter between the succeeding staples in the 60 raceway.

30. In a button-attaching machine, a raceway arranged to hold buttons and associated staples, an anvil at one extremity of the raceway, a reciprocatory and oscillatory

driver co-operating with the raceway and 65 anvil, a cam controlling the movement of the driver in one direction, and a lever controlling its movement in another direction, said cam and lever effecting their control independently.

31. In a machine for attaching fasteners, a work-support, attaching mechanism co-operating therewith, work-retaining means, actuating means for moving the retaining means toward the support, a member 75 through which the movement is transmitted, and means acting upon the member and arranged to move the retaining means from the support upon movement of the actuating means in the same direction. 80

32. In a machine for attaching fasteners, a work-support, attaching mechanism co-operating therewith, combined fastener-conveying and work-retaining means, actuating means for moving the conveying and 85 retaining means toward the support, a member through which the movement is transmitted, and a spring acting upon the member and arranged to move the conveying and retaining means from the support upon 90 movement of the actuating means in the same direction.

33. In a machine for attaching fasteners, a work-support, attaching mechanism co-operating therewith, means for retaining the 95 work upon the support during the attachment of the fasteners thereto, actuating means for moving the retaining means toward and from the support, there being provision for lost motion between the actuating 100 means and the retaining means, and means acting independently of the actuating means for moving the retaining means during the period of lost motion.

34. In a machine for attaching fasteners, 105 a work-support, attaching mechanism co-operating therewith, means for retaining the work upon the support during the attachment of the fasteners thereto, actuating means for moving the retaining means toward and from the support, there being provision for lost motion between the actuating 110 means and the retaining means, and a spring operating upon the retaining means during the period of lost motion. 115

35. In a machine for attaching fasteners, a work-support, fastener-attaching means and work-retaining means independently mounted for movement toward and from the support, an independently movable actuating member for each of said means, driving means joined to one actuating member, and connections between the actuating members to transmit movement from the driving member to the other actuating 120 member. 125

36. In a machine for attaching fasteners, a work-support, fastener-attaching means

and work-retaining means independently mounted for movement toward and from the support, an independently movable actuating member for each of said means, 5 yieldable connections between one of the means and the corresponding actuating member, driving means joined to one actuating member, and connections between the actuating members to transmit movement from the driving member to the other actuating member.

37. In a machine for attaching fasteners, a work-support, fastener-attaching means and a fastener-supporting and work-retaining means independently mounted for movement toward and from the support, an independently movable actuating member for each of said means, driving means joined to one actuating member, and connections between the actuating members to transmit movement from the driving member to the other actuating member.

38. In a machine for attaching fasteners, a work-support, attaching mechanism co-operating therewith, a fastener-conveyor movable into co-operation with the support, and an actuating member movable into contact with a surface carried by the conveyor to effect its travel, there being a space between the actuating member and contact surface through which space the conveyor may move to produce a fastener-feeding concussion.

39. In a machine for attaching fasteners, an anvil, a driver co-operating therewith, a fastener raceway movable into contact with the work upon the anvil, and an actuating member movable between opposite surfaces carried by the raceway to operate the raceway in opposite directions, said member being normally spaced from one of the surfaces.

40. In a button-attaching machine, an anvil, a raceway for buttons and associated staples movable into co-operation with the anvil, a staple driver co-operating with the anvil, a lever connected to the driver, driving mechanism joined to said lever, a lever connected to the raceway, and actuating connections between the levers.

50. 41. In a button-attaching machine, an anvil, a raceway for buttons and associated staples movable into co-operation with the anvil, a staple driver co-operating with the anvil, a lever connected to the driver, driving mechanism joined to said lever, a lever yieldably connected to the raceway, and actuating connections between the levers.

42. In a button-attaching machine, an anvil, a raceway for buttons and associated staples movable into co-operation with the anvil, a staple driver co-operating with the anvil, a lever connected to the driver, driving mechanism joined to said lever, a lever connected to the raceway, and actuating connec-

tions between the levers, said connections 65 providing for lost motion.

43. In a button-attaching machine, an anvil, a raceway for buttons and associated staples, a staple feeder and driver co-operating with the raceway, a lever connected to the feeder and driver, driving mechanism joined to said lever, a lever connected to the raceway, and actuating connections between the levers.

44. In a button-attaching machine, a frame, an anvil mounted thereon, a raceway for buttons and associated staples movable upon the frame into co-operation with the anvil, a lever fulcrumed upon the frame, a staple feeder and driver pivoted upon the lever for co-operation with the raceway and anvil, driving mechanism joined to the lever, a second lever fulcrumed upon the frame and being connected to the raceway, and pin-and-slot connections between the levers.

45. In a button-attaching machine, a frame, an anvil mounted thereon, a raceway for buttons and associated staples movable upon the frame into co-operation with the anvil, a lever fulcrumed upon the frame, a staple feeder and driver pivoted upon the lever for co-operation with the raceway and anvil, driving mechanism joined to the lever, a second lever fulcrumed upon the frame, a yieldable contact member carried by the raceway and engaged by the last-mentioned lever, and a pin-and-slot connection between the levers.

46. In a button-attaching machine, a frame, an anvil mounted thereon, a raceway for buttons and associated staples, a lever fulcrumed upon the frame, a staple feeder and driver pivoted upon the lever, a spring connecting the lever and staple feeder to draw the latter toward the raceway, and driving mechanism joined to the lever.

47. In a button-attaching machine, a frame, an anvil mounted thereon, a raceway for buttons and associated staples, a lever fulcrumed upon the frame, a staple feeder and driver pivoted upon the lever, a cam, a spring connecting the lever and staple feeder to draw the latter toward the cam and raceway, and driving mechanism joined to the lever.

48. In a button-attaching machine, a frame, an anvil mounted thereon, a raceway for buttons and associated staples, a lever fulcrumed upon the frame, a staple feeder and driver pivoted upon the lever, a spring connecting the lever and staple feeder to draw the latter toward the raceway, driving mechanism joined to the lever, and means to carry the staple feeder away from the raceway during a portion of its travel.

In testimony whereof I have signed my name to this specification.

WILLIAM E. ELLIOTT.
